UNITED STATES PATENT OFFICE.

JOHN E. TESSEYMAN, OF CHICAGO, ILLINOIS, ASSIGNEE TO RELIABLE RAILWAY EQUIPMENT COMPANY, OF CHICAGO, ILLINOIS, A CORPORATION OF ILLINOIS.

UNCOUPLING DEVICE.

Application filed April 1, 1922. Serial No. 548,600.

To all whom it may concern:

Be it known that I, JOHN E. TESSEYMAN, a citizen of the United States, residing in Chicago, in the county of Cook and State of Illinois, have invented a new and useful Improvement in Uncoupling Devices, of which the following is a specification.

This invention relates to uncoupling devices for car couplings and has for an object 10 to provide a simple and efficient uncoupling device embodying in its construction a pin-operating connection between the uncoupling lever and the locking pin of the car coupling, which connection permits both longitudinal and lateral movement of the car coupling without danger of being disengaged from its connected parts, with the result that operative relations of the parts are maintained regardless of displacements of 15 the coupling. The invention is further characterized by an entire adaptability to standard uncoupling levers and standard couplings and may be quickly applied, without any change in the construction of these 20 standard parts.

In addition to the general objects recited above, the invention has for further objects such other improvements or advantages in construction and operation as may be found 25 to obtain in the structures and devices hereinafter described or claimed.

In the accompanying drawings forming a part of this specification and showing, for purposes of exemplification, a preferred 30 form and manner in which the invention may be embodied and practiced, but without limiting the claimed invention specifically to such illustrative instance or instances:—

Figure 1 is a fragmentary sectional view 35 of the end of a railway car showing the application of an uncoupling device constructed in accordance with the improvements of the present invention;

Fig. 2 is a perspective view of the un- 40 coupling device; and

Fig. 3 is a detailed top plan view of one 45 of the members of the uncoupling device.

The same characters of reference designate the same parts in each of the several 50 views of the drawings.

In the illustrated embodiment of the invention, the end sill of a railway car is indicated at 11 and a car coupling is indicated at 12, said coupling being of a standard type provided with a locking pin or block

13, which, when lifted, releases the coupling 12 and permits it to uncouple from a companion coupling carried by an adjacent car. The coupling pin 13 is provided at its upper end with an eye 14 which receives one 60 end of the pin-lifting connection, as will be hereinafter set forth.

Bolted to the car end, above the end sill 11, is a bracket 15, in which is rotatably supported the shaft 16 of a standard uncoupling lever. The said uncoupling lever is provided at its inner end with an arm 17 which extends longitudinally of the car and outwardly from the end sill over the pin 13 of the coupling; and said lever is further 70 provided at its outer end with the usual handle (not shown) which is operated in a counter-clockwise direction, as viewed in Fig. 1, to lift the outer end of the arm 17 and to effect the uncoupling operation. At 75 its outer end, the arm 17 is provided with an eye 18 which receives the upper end of the pin-lifting connection.

In accordance with the invention, the pin lifting connection between the uncoupling 80 arm 17 and the pin 13 is constituted of a pair of members 19, 20 connected together so as to have relative swinging movements in all directions in addition to relative sliding movements, with the result that the connection may readily accommodate itself to either lateral, longitudinal or vertical displacements of the coupling 12 without straining or disturbing the operative relations of the parts of the uncoupling as- 85 sembly. For this purpose, the members 19, 20 are formed at their connected ends with closed loops 21 preferably elliptical in shape and providing similarly-shaped eyes 22, the loop 21 of each member being inserted in 90 the eye 22 of the other, as shown. With this construction, the connected members 19, 20 may not only move freely toward each other, i. e.,—vertically, but are also capable of practically universal movement with re- 95 spect to each other.

At their respective upper and lower ends the members 19, 20 are formed with hooks 100 23 and 24 for insertion into the eyes 18 and 14 of the arm 17 and the pin 13, in applying the pin-lifting connection. As shown, the hooks 23 and 24 are respectively formed with rebent portions 25 and 26 that extend 105 backwardly of the main portions of the hooks and across the parts with which said 110

hooks are connected, to prevent disengagement of the hooks from their connected parts, during swinging or other movement of the members 19, 20.

5 The invention as hereinabove set forth is embodied in a particular form of construction, but may be variously embodied within the scope of the claims hereinafter made.

I claim:

- 10 1. An uncoupling device comprising two members formed of bent rod of like shape and size, each rod having one end bent to provide an open scroll-like hook and having the other end bent to form a closed elongated loop, the elongated loops of the two members being loosely linked with each other.
- 15 2. An uncoupling device having two

members formed of bent rods, each rod having one end bent to provide a vertically and a laterally extending open hook and having the other end rebent upon itself to provide an elongated closed loop, the closed loop portions of said rods being loosely connected to each other.

25 3. An uncoupling device having two members formed of bent rods, each rod having one end bent to provide a vertically and a laterally extending open hook and having the other end rebent upon itself to provide an elongated closed loop in a normally vertical plane, the closed loop portions of said rods being loosely connected to each other by one loop passing through the other.

JOHN E. TESSEYMAN.
